UNITED STATES PATENT OFFICE.

GEORGE A. SIMS, OF ERIE, PENNSYLVANIA.

FLUID-HEATER.

1,096,273.

Specification of Letters Patent. Patented May 12, 1914.

Application filed January 12, 1912. Serial No. 670,883.

To all whom it may concern:

Be it known that I, GEORGE A. SIMS, a citizen of the United States, residing at Erie, in the county of Erie and State of Pennsylvania, have invented certain new and useful Improvements in Fluid-Heaters; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to fluid heaters and consists in certain improvements hereinafter set forth and described.

The features of my invention are illustrated in the accompanying drawings as follows:

Figure 1, is a side view elevation of a fluid heater embodying my invention, with portions of the shell thereof broken away, showing portions of the fluid heater in vertical section. Fig. 2, is an end view thereof, looking in the direction of the arrow "w" in Fig. 1, with closure plates removed. Fig. 3 is a transverse section of the same on the line $x-x$ looking in the direction of the arrow "y" in Fig. 1. Fig. 4, is a like section through the shell only of the heater, looking in the direction of the arrow "z" in Fig. 1, showing the spiral deflector secured in the end plate of the heater.

In these drawings A indicates the shell of the fluid heater, which is preferably cylindrical in shape. Within one end of the shell A, I place a hollow, annular header B, which is supported upon a rib b, which rests upon and is secured against the lower interior wall of the cylinder A. In the opposite end of the cylinder A, I secure a head A', and in the upper portion of this head A', there is a segmental opening a. On the inside of the head A' over the segmental opening a, is secured a segmental header plate A².

Extending between the segmental header plate A² and the uppermost segment of the annular header B in the opposite end of the cylinder A are tubes C the ends of which are secured in the header plate A and in the annular header B in the usual manner. Access to the interior cavity of the annular header B is had through openings in the side thereof, which are closed by means of

screw plugs b' as shown in Fig. 1. Each one of said screw plugs b', being on the axial plane of its corresponding tube C, so that a tool may be inserted through the hole 60 occupied by a plug b' for the purpose of expanding the ends of the tubes C to secure them in the header B, after which operation the plugs b' are inserted and screwed into the holes in the header B. The segmental header at the opposite end of the cylinder A is closed by means of a closure plate D screwed over the segmental opening a by means of tap-bolts d and is provided with an opening d' adapted to have 70 a pipe connected thereto. In the lower portion of the cylinder head A', is another opening in which there is secured a segmental header E. Extending between the header E and the lower-most segment of the 75 header B, in the opposite end of the cylinder A, are tubes C', the ends of which are secured in the headers B and E, as herebefore described with relation to the upper tubes C. The header E is closed by means of a 80 closure plate E' secured over the face thereof, by means of bolts e in the usual manner, the plate E' being provided with an opening e' to which a pipe may be coupled. In the upper wall of the cylinder A adjacent to the head A' is a pipe F which communicates with the interior of the cylinder, and in the lower wall of the cylinder A adjacent to the header B I secure another pipe F'. The end of the cylinder A adjacent to 90 the header B is closed by means of a cylinder head A³. In an opening a² in the central portion thereof, is secured a spiral or tangential fluid jet G with which is connected a fluid supply pipe G' leading from a source 95 of fluid supply.

In operation a heat conveying medium is introduced into the tubes C or C' through one of the pipe openings d' or e'. If a heat conveying medium such as exhaust steam, 100 is introduced into the header E through the pipe opening e' it will travel through the tubes C' and through the hollow, annular header B and thence through the tubes C to the segmental header A² and out through 105 the pipe opening d', thus completing a circuit, longitudinally of the cylinder, through the tubes C and C', thus heating the same.

Fluid to be heated is introduced into the cylinder A through the supply pipe G' and 110 the spiral jet G and flows from the cylinder A by means of the pipe F in the upper wall

thereof. It will be seen that by means of the spiral jet G the fluid to be heated within the cylinder A will be given a spiral rotation, thereby causing all the particles of fluid to come in contact with the heated tubes C and C' and header B.

In case it is desirous of drawing off the fluid within the cylinder A the same may be accomplished by means of the pipe F' in the 10 manner usual with such apparatus.

From the foregoing description, the construction and operation of my improved fluid heater is so obvious that further description thereof is deemed unnecessary.

15 Therefore, having fully described and illustrated my invention so as to enable others to construct and operate the same, what I claim as new and desire to secure by Letters-Patent is:—

10 The combination in a fluid-heater of a hollow, cylindrical shell, a head closing one end

thereof having an opening therethrough for the introduction of fluid to be heated, a head in the other end of said shell having substantially semi-circular openings there-through adjacent to the upper and lower edges thereof, tube-header plates secured on the inside of said shell-head, covering said openings, a hollow, annular tube-header within said shell, tubes extending between 25 and connected to said semi-circular header-plates and said hollow, annular header, and closure-plates having pipe connections thereon secured to the outside of said shell head and covering the semi-circular openings 30 thereof, substantially as set forth.

In testimony whereof I affix my signature, in presence of two witnesses.

GEORGE A. SIMS.
